CLAIM

The ornamental design for a portable dermal freezing unit handle, as shown and described.

DESCRIPTION

FIG. 1 is a perspective view of a portable dermal freezing unit handle according to the present invention, wherein the applicator end is shown in phantom and forms no part of the claimed design;

FIG. 2 is an elevation front view of the portable dermal freezing unit handle of FIG. 1, the rear view being identical thereto, wherein the applicator end is shown in phantom and forms no part of the claimed design;

FIG. 3 is an elevation side view of the portable dermal freezing unit handle of FIG. 1, the opposite side view being identical thereto, wherein the applicator end is shown in phantom and forms no part of the claimed design;

FIG. 4 is a top plan view of the portable dermal freezing unit handle of FIG. 1, wherein the applicator end is shown in phantom and forms no part of the claimed design; and,

(Continued)

FIG. 5 is a bottom plan view of the portable dermal freezing unit handle of FIG. 1 wherein the ovals shown in phantom form no part of the claimed design.

1 Claim, 1 Drawing Sheet
